UNITED STATES PATENT OFFICE.

MORRIS LOWY, OF NEW YORK, N. Y.

CORNER FASTENING FOR BEDSTEADS.

Application filed October 26, 1921. Serial No. 510,415.

To all whom it may concern:

Be it known that I, MORRIS LOWY, a citizen of the United States, and resident of the city of New York, in the county of Kings and State of New York, have invented certain new and useful Improvements in Corner Fastenings for Bedsteads, of which the following is a specification.

The present invention relates to improvements in corner-fastenings for bedsteads, and has for its main object to provide a simple, efficient and durable device of this type which is made by stamping operations.

Another object of the invention is to produce a corner-fastening of the type specified, which permits of a convenient assembling of the bed and of a taking down of the same by inexperienced operators with but little time and energy.

20 A further object of the invention is to so construct the corner-fastening that the bed-bottom supporting member may be clamped thereto or released therefrom by an element that forms part of the corner-fastening, there being thus no chance of losing or misplacing the clamping member.

With these and other objects in view, which will more fully appear as the nature of the invention is better understood, the 30 same consists in the combination, arrangement and construction of parts hereinafter described, pointed out in the appended claims and illustrated in the accompanying drawings, it being understood that many 35 changes may be made in the size and proportion of the several parts and details of construction within the scope of the appended claims, without departing from the spirit or sacrificing any of the advantages of 40 the invention.

One of the many possible embodiments of the invention is illustrated in the accompanying drawings, in which:—

Figure 1 is a perspective view of a portion of the corner-post of a bedstead with a corner-fastening, constructed in accordance with the present invention, in position thereon; Fig. 2 is a side elevation of the elements shown in Fig. 1; Fig. 3 is a section taken on line 3—3 of Fig. 2; Fig. 4 is a section taken on line 4—4 of Fig. 2; and Fig. 5 is a plan view of the blank of which the shell of the fastening is made.

In the drawings, the numeral 10 indicates 55 a portion of a rectangular corner-post of a

bedstead, to which the corner-fastening is to be attached. The corner-fastening includes a bracket-like hollow rectangular shell 11, preferably, made of one integral piece, for instance by stamping operations from a 60 blank 12, shown in Fig. 5 of the drawings. This shell includes a top wall 13, an inner side wall 14, an outer side wall 15, from which extends inwards toward the wall 14 a bottom portion 16. From the said bottom 65 portion rises a plate member 17, the upper section of which is inclined, as shown at 18; said inclined portion extending toward the upper edge of the outer side wall 15. From the inner side wall 14 extends toward the 70 outer side wall 15 a bottom portion 19, merging into a vertical plate member 20, that extends parallel to the plate member 17 and is then bent back toward and into contact with the side wall 14, as clearly shown at 21. The 75 shell elements so far described extend longitudinally of the bedstead, that is to say at right angles to the longitudinal axis of the corner-post 10, and serve to receive, in a manner hereinafter to be described, the bed- 80 bottom supporting angle bar 22. The shell includes furthermore end members 23, one of which engages the corner-post, while the other abuts against the first-mentioned end member. The end members project a sub- 85 stantial distance below the bottom portions above referred to, screw bolts 24 passing through the said end members into the corner-post and serving to attach the shell to the said post.

The shell, as described, constitutes a hollow rectangular body, adapted to receive one end of the angle bar 22, the horizontal flange 25 of the said angle bar abutting against the inner face of the top wall 13 of the shell, 95 and the vertical flange 26 of the said angle bar abutting against the inner face of the outer side wall 15 of the shell. The vertical flange of the said angle bar rests upon the bottom portion 16 of the shell, and the free 100 edge of the inclined portion 18 of the plate member 17 is adapted to engage the inner face of the bend between the two flanges of the angle bar, as will hereinafter appear.

The plate member 17 and its inclined portion 18 are capable of yielding, constituting thus a jaw that is adapted to be forced against the angle bar 22. For effecting this clamping operation, there is a lever 27 pivoted to the shell 11, the pivot being in the 110

form of a screw bolt 28, that extends through the inner wall 14, the plate member 20 and plate member 17. The outer end of the said screw bolt is provided with a head 29, 5 abutting against the outer face of the side wall 14, and its inner end is screw-threaded. The said threads mesh with those of a nut 30, which abuts against the plate member 17 and is disposed between the said plate member 10 and the outer side wall 15. The lever is provided with a side cam face 31, adapted to co-operate with a lug 32, formed upon the plate member 17. The lever is furthermore provided with an end cam face 33, capable 15 of co-operating with the inner face of the horizontal flange 25 of the angle bar 22. The two cam faces are on a vertically extending section 34 of the lever, the latter being provided with a horizontally extending 20 handle portion 35, that extends inwards toward the longitudinal center line of the bedstead. The plate member 20 and its horizontal portion 21 constitute a spacing element, serving to hold the lever 27 in proper 25 relation to the lug 32 above mentioned.

The two shells 11 on the corner-posts, forming an end member of the bedstead, may be connected in any suitable manner, for instance by an angle bar 36, which is 30 fastened by screws 37, or otherwise, to lugs 38, which are, preferably, made integral with the two shells.

The operation of the corner-fastening is as follows: When an angle bar is to be inserted 35 into the shell, the lever 27 is shifted around its pivot in the direction of the arrow shown in Fig. 2 of the drawings until its side cam face is disengaged from the lug 32 and its end cam face is disposed at a 40 distance from the top wall 13 of the shell sufficient to permit of a convenient insertion of the angle bar. After the angle bar has been put into place, the lever 27 is shifted into the position shown in the several 45 figures of the drawing, whereby the inclined portion 18 of the plate member 17 is forced against the angle bar, thereby clamping the latter against the outer side wall 15. Simultaneously therewith, the end cam face of 50 the lever clamps the horizontal flange of the angle bar against the top wall of the shell.

If it is intended to disengage the angle bar from the shell, obviously the lever 27 55 must be brought into a position to disengage its cam faces from the lug 32 and the angle bar.

Attention is called to the fact that the ends 60 of the angle bars, engaging the shells or corner blocks of the bedstead, have no weakened portions at all, as in the constructions heretofore in use, in which it is usually necessary to cut out or remove sections on the ends of the angle bars for engagement with 65 projections or bolts on the corner blocks.

From the foregoing it appears that the mechanism for detachably fastening the angle bar to the shell is permanently fastened to the latter, with the result that it cannot be lost or misplaced.

It appears from the drawings that the casting 11 is of a length sufficient to form a proper support for the angle bar, and the cam faces, with their co-operating elements, securely fasten the angle bar in place, and 75 yet the latter may be readily detached for the proper purpose of taking down the bed and putting it together again by inexperienced operators with but little time and energy.

It is to be observed that, while herein the shell has been described as made of one integral piece made by stamping operations, the same may be otherwise produced without departing from the invention.

What I claim is:—

1. In a corner-fastening for bedsteads, the combination with a corner-post, of a hollow rectangular shell fastened thereto, an angle bar of the bed-bottom supporting frame extending into said shell, said shell including a rigid portion engaging the outer face of said angle bar and a yielding portion capable of being brought to bear against the inner face of said angle bar, said yielding portion being provided with a lug, and a cam lever mounted on said shell and co-operating with said lug for causing the yielding portion of said shell to clamp said angle bar against the rigid portion thereof, and means 100 made integral with said shell for spacing said lever from one of the side walls of said shell and keeping the same in operative relation to said lug.

2. In a corner-fastening for bedsteads, the combination with a corner-post, of a hollow rectangular shell fastened thereto, said shell including two parallel side walls, a top, a bottom portion extending from one of said side walls toward the other side wall and merging into an upwardly extending plate member between said side walls, said plate member having an inclined portion extending toward the junction line of said top wall and side wall to which said bottom is connected, and a bottom portion extending from the other side wall toward said plate member and merging into a plate member extending parallel to said first-mentioned plate member and thence extending back into contact with its respective side wall, said first-mentioned plate member being yieldable, an angle bar of the bed-bottom supporting frame extending into said shell with its horizontal flange in abutment with the inner 110 face of said top wall and with its vertical flange in contact with the side wall that co-115 operates with said yielding plate member, said vertical flange resting upon said first-mentioned bottom portion, and a lever piv- 120

oted to said shell between said plate members, said lever having a cam face for causing the inclined portion of said yielding shell section to clamp said angle bar against one of said side walls, said lever having a further cam face adapted to bear against the horizontal flange of said angle bar and

capable of clamping the same against the top wall of said shell.

Signed at New York in the county of 10 New York and State of New York, this 26th day of September, A. D. 1921.

MORRIS LOWY.
